UNITED STATES PATENT OFFICE.

CHARLES J. JOHNSON, OF CEDAR RAPIDS, IOWA, ASSIGNOR TO THE JOHNSON GAS APPLIANCE CO., OF CEDAR RAPIDS, IOWA.

TINSMITH'S FURNACE.

1,088,230.

Specification of Letters Patent. Patented Feb. 24, 1914.

Application filed July 14, 1913. Serial No. 779,038.

To all whom it may concern:

Be it known that I, CHARLES J. JOHNSON, a citizen of the United States, residing at Cedar Rapids, in the county of Linn and State of Iowa, have invented certain new and useful Improvements in Tinsmiths' Furnaces, of which the following is a specification.

This invention relates particularly to furnaces or heaters used by tinsmiths for heating their soldering coppers, though the furnace is in practice applicable to various other uses.

The chief object of the invention is to produce a simple and convenient heater of this sort, using a Bunsen burner, adapted for the quick and safe heating of soldering coppers, tempering and forging of tools, and other like operations requiring but a limited heat.

The invention therefore consists in the structure of parts and in their combination for the purpose specified substantially as hereinafter set forth and claimed.

In the accompanying drawings which form a part of this specification, Figure 1 represents the invention in plan, the hood being thrown back; Fig. 2 shows a longitudinal, vertical, medial section of the furnace in operation; and Fig. 3 is a front elevation 30 of the furnace with the hood removed.

In the drawing, A designates the main casting or base of the furnace provided with legs a, a well b and lugs c, to which is pivoted a hood B. Through a hole in the front 35 of the well slightly projects the nozzle of the Bunsen burner C, which has a branch d, provided with a pilot tube e, and mounted upon the supply pipe D. A stop-cock E, provided with a lever F, regulates the flow 40 of gas in the burner. A pinion h meshes with a small gear i, which is a part of the needle-valve regulator, but forms no essential feature of this invention. The burner is inclined so that the flame is projected 45 toward the back and upper part of the well where the point of a copper is located when heating. It is desirable, however, to protect the tinned point of the copper against the corroding action of the direct contact 50 with the gas flame; therefore a rest G for the points of the coppers is mounted upon the base at the rear of the well and is provided

with an upright rib or flange g to serve as a stop or limit for said points. This ledge is far enough from the front edge of the rest 55 to permit the tinned point to project beyond the path of the flame. A non-conducting lining H of asbestos is preferably provided. The curvature of the hood is such that it serves to deflect the flame back upon the copper 60 thereby heating the whole copper uniformly without having to turn the copper.

When it is desired to heat something too large to enter the muffle the hood is turned back and such object set upon the base over 65 the well and burner.

The burner is preferably supported between the front legs of the furnace upon trunnions I and the supply pipe by a hanger J at the rear end of the furnace. To aid in 70 securing complete combustion during low pressure of gas, air holes f may be provided in the front wall of the well.

The invention claimed is:

1. In a tinsmith's furnace the combination 75 of a base having a tool support and a well to the rear of said support and below it, a burner attached to said base and projecting diagonally upward and rearward into the well, and a hood hinged at the rear of the well and forwardly curved in a manner such as to deflect the heat forward and downward toward the well for the purpose set forth.

2. In a tinsmith's furnace the combination 85 of a base having a tool support and a well at its rear and below the level of the tool support, a burner mounted at the front of the furnace and projecting obliquely upward into said well to direct the flame to the 90 rear of the furnace, a forwardly curved hood hinged to the base back of the well and forwardly curved in a manner such as to deflect the heat forward and downward toward the well, and a rest consisting of an angle- 95 plate having an upwardly extending limiting rib and mounted at the back end of the well for the purpose specified.

In testimony whereof I have affixed my signature in presence of two witnesses.

CHARLES J. JOHNSON.
